UNITED STATES PATENT OFFICE

2,209,005

SERIES LAMP

Alfred Sittel, Schoneiche, near Berlin, Germany,
assignor to General Electric Company, a corporation of New York

Application June 27, 1939, Serial No. 281,494
In Germany July 4, 1938

3 Claims. (Cl. 176—24)

My invention relates to electric incandescent lamps for series operation, and more particularly to an automatic cut-out device for such lamps which will prevent the extinguishment of all the lamps in the series upon the failure of any one lamp.

Electric incandescent lamps for series connection are as a rule equipped with a normally insulating breakdown fuse or cut-out member so that when the filament of a lamp fails, the cut-out is rendered conductive and the other lamps of the group will continue to burn by an automatic short circuiting of the lamp; or if the failure occurs while the filament is unlighted, the other lamps of the group may thereby be placed in operation merely by closing the circuit. The cut-outs used for such incandescent lamps operated in a series circuit have been designed in many different ways. Generally they consist of oxidized aluminum wires or aluminum strips which are placed around the two current supply wires of the lamps within the stem tube of the lamp. These cut-outs respond with great reliability when the filament of the lamp breaks when it is not burning and therefore while it is cold, but they do not respond as reliably when the filament fails while burning. In the latter case it happens, particularly when the series-connected incandescent lamp operates in circuits with voltages in excess of 220 volts, such as in circuits for electric railways, that between the broken ends of the filament an arc is formed which takes up the partial voltage of the point of the break. As a result, the current will continue to flow over the filament, and the full network voltage which is required for breaking down the cut-out is therefore never impressed thereupon. If an arc should occur, it may readily extend itself to the current supply wires while the current increases, and then frequently leads not only to a destruction of the lamp bulb but also of the base and of the fitting. In extreme cases, even the connection cable may catch fire.

This disadvantage, which occurs in electric incandescent lamps connected in series, can be avoided when, according to the invention, the current supply wires are not only bridged by a cut-out, but when in addition they are brought so close to each other at a point between the filament and the stem tube that the parts of the current supply wires located at the point of proximity are melted together when an arc occurs. Since the arc is extinguished when the current supply wires melt together, no damage can be caused to the base, to the fitting and to

the connection cable by any arc which may be formed within the lamp and which may extend further or become unnecessarily long. The melting together of the current supply wires also assures the continued uninterrupted passage of the current through the other lamps of the group so that the latter cannot be extinguished as a result of the filament failure. When, in the described lamp according to the invention, a failure of the filament occurs while in the cold state, then the cut-out of the damaged lamp will immediately respond when the lamp group is switched on. In such case, no arc will be formed at the broken filament.

At the time during which carbon-rod filaments were used in electric incandescent lamps, it was occasionally suggested to bring the current supply wires which supported the carbon-rod filaments, close together at a point below the filament, for series-connection purposes, so that when the filament burned through, the arc that might be formed would melt together the parts of the current supply wires that were brought close to each other, for the purpose of establishing a current path. However, this suggestion did not, by itself, gain practical importance either for the lamps with carbon-rod filaments used at that time or for lamps with filaments made of tungsten wire that were used subsequently. The reason for this was that on the one hand, such a measure fails when the filament breaks while cold and consequently does not prevent the extinguishment of the lamps of the entire group when the circuit is switched on again, and in the second place because when the filament fails during operation, an arc which would cause the melting together of the current supply wires is not always formed, and is formed but rarely in the case of series-connection lamps burning in circuits of 110 to 220 volts, as is the case for instance with illuminating lamps and candle-type lamps.

One object of my invention is to provide means for series-operating electric incandescent lamps which will prevent the extinguishment of all the lamps in the series upon the failure of any one lamp therein.

Another object of my invention is to provide automatic cut-out means for series-operating electric incandescent lamps which will positively operate to short-circuit the lamp filament and interconnect the lamp leading-in wires upon failure of the said filament, regardless of whether such failure occurs during lamp operation or otherwise.

A feature of the invention is the use of inner leads having portions lying in close proximity to each other together with a cut-out bridging the lamp leading-in wires and spaced a considerable 5 distance from the point at which the said leads approach each other. A further feature of the invention is the provision of a spacing member to hold the inner leads at a definite predetermined distance from each other.

10 Further objects and advantages of my invention will appear from the following description and from the accompanying drawing which is an elevation, partly in section, of an electric incandescent lamp comprising my invention for 15 series operation, and in particular, for use on railroad trains with trolley-wire voltages in excess of 440 votes.

Referring to the drawing, the lamp there shown consists in the customary manner of a glass bulb 1, a stem tube 2 extending inwardly of the bulb, two current supply or leading-in wires 4, 5 hermetically sealed in the stem press 3 of the stem tube, a sealed evacuation tube 6, and a filament 7 which may consist of a single or double coil 20 of tungsten wire and which is welded, or fastened by pinching, to the ends of the two current supply wires 4, 5. One of the said wires is soldered to the sleeve 8, and the other to the bottom contact 9 of a customary screw base. 25 The outer leads 4', 5', i. e., the parts of the two current supply wires which extend between the stem press 3 and the lamp base, are bridged by a clamp of oxidized aluminum strip 10 which constitutes the breakdown fuse or cut-out of the 30 lamp. This cut-out always responds when the filament 7 fails while cold, and under certain circumstances will also respond when the filament fails in the heated condition. The latter response occurs when an arc is not immediately 35 formed upon failure of the filament during operation, so that the lamp is consequently extinguished. Between the coiled filament 7 and the stem press 3 of the stem tube 2, the two inner leads 4, 5 of the current supply wires are provided with two acute-angle impressions 11, 12 40 which are directed toward each other and which approach each other to a distance of 1 mm. or less. If, when the filament fails during lamp operation, an arc is formed between the broken 45 ends of the filament, and when this arc, as customarily occurs, passes down along the current supply wires 4, 5, towards the stem press 3, then the parts of the impressions 11, 12 which are located in close proximity to each other will be 50 melted together by the arc, with resultant extinguishment of the arc. In order to prevent the inner current supply wires 4, 5 from springing apart when the filament 7 fails in the heated 55 condition and when an arc is formed, and in

order to insure a melting together of the current supply wires with great reliability, the said inner leads are bridged, in an insulated manner, by means of a spacer member comprising a glass bead 13 which is held by wires 14, 15 welded to 5 the inner current supply wires. The said spacer member maintains the spaced relation of the inner leads 4, 5 at all times.

The shape of the filament, of the lamp bulb and of the base may be any desired one. The 10 cut-out 10 may also be of any other suitable construction, and can in certain cases, as known, be located within the bulb instead of externally thereof.

What I claim as new and desire to secure by 15 Letters Patent of the United States is:

1. An electric incandescent lamp comprising a sealed envelope, a filament within said envelope, a base secured to said envelope, and a pair of leading-in wires connecting said filament to the 20 terminals of said base, said leading-in wires including inner leads within said envelope having bent portions extending into sufficiently close proximity to each other so that an arc formed upon failure of said filament and passing along 25 said leads will fuse them together at their said bent portions, and a cut-out member bridging said leading-in wires at a point intermediate the base connections and the closely disposed portions of said leading-in wires, said cut-out member being spaced a considerable distance from the said closely disposed portions of said leading-in wires and being normally non-conductive but becoming automatically conductive upon application 30 of an abnormal voltage to the lamp. 35

2. An electric incandescent lamp comprising a sealed envelope, a filament within said envelope, a base secured to said envelope, and a pair of leading-in wires connecting said filament to the terminals of said base, said leading-in wires including inner leads within said envelope having bent portions extending into close proximity to each other, and a cut-out member bridging said 40 leading-in wires externally of said envelope.

3. An electric incandescent lamp comprising a sealed envelope, a filament within said envelope, a base secured to said envelope, and a pair of leading-in wires connecting said filament to the terminals of said base, said leading-in wires including inner leads within said envelope having bent portions extending into close proximity to 45 each other, a cut-out member bridging said leading-in wires externally of said envelope, and a spacer member bridging said leading-in wires internally of said envelope and maintaining the said bent portions of said leading-in wires in 50 definite close proximity to each other. 55
